GASPROOF LITTER COVER

William D. Fleming, Edgewood Arsenal, Md.

Application December 12, 1941, Serial No. 422,652

2 Claims. (Cl. 5—82)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to chemical protective equipment in general, and more specifically to the prevention of effective use of chemical warfare agents by the enemy against field and/or hospitalized casualties.

As a result of two decades of intense study and development, material progress has been made, through improvements in gas masks and garments of impervious material, toward solving the problem of anti-gas protection.

However, and as is apparent, while gas masks and clothing which form equipment for protecting the soldier against chemical warfare may be readily donned by the soldier possessing combat vigor, the clumsiness of such an outfit and/or its several parts makes difficult and sometimes renders impossible, the placement or fitting thereof to a casualty either in the field, or in a hospital, or at treatment centers.

It is seen readily that quite a number of difficult situations arise with the problem of protecting casualties against exposure to chemical warfare agents or gases either while in the process of removal from the zone of battle, or during evacuation of field and base hospitals, or where, because of the circumstances, casualties must be kept in the area where the gas attack is in progress.

The nature of the equipment above referred to is indicative of the fact that complete protection against war gases involves prevention against inhaling or breathing of these agents, and prevention against contact of the gases with any part of the human body. The need of such preventions may be further explained by noting that for convenience war gases have been divided in groups, to which, for an appreciation of the advantages of this invention, reference is broadly made only to "lung irritants" so called because it is necessary to breathe these agents in order to produce any marked effect; "sternutators" or irritant smokes and vomiting gases; "vesicants" which produce a blistering action on any part of the human body with which they come in contact; and "lacrimators" which produce a powerful irritant action on the eyes.

Up to the present time, no effective and otherwise satisfactory means had been developed whereby, without resort to the usual protective equipment, namely, gas masks and protective clothing, casualties, either while being carried

from the zone of combat on litters or field stretchers, or while being transported to field or base hospitals in ambulances, or while bed-ridden in such hospitals, could, with minimum discomfort to the casualty, be readily and adequately protected against all chemical agents.

In considering protection of the casualty from direct exposure to chemical warfare irritants, consideration had also to be given to effectively guarding the litter, stretcher, bed or other form of body-rest against contamination. Otherwise contact of the patient with a contaminated part of such body-rest might result, especially where persistent vesicant agents are used by the enemy, in defeating the objective sought, namely, complete, dependable and effective protection of the casualty against all chemical agents when and where needed.

Accordingly, I have devised a simple and effective medium whereby not only may the patient, but also the litter, stretcher, bed, or other form of body-rest upon which he is recumbent, be readily and effectively protected from the deleterious effects of chemical warfare agents; and the invention, together with its objects and advantages, will be best understood and appreciated from a study of the following detailed description, made in connection with the accompanying drawing, wherein—

Figure 1 is a perspective view of a litter embodying the features of my invention, and illustrating manner of using same for protecting a casualty.

Figure 2 is a perspective view of the litter in rolled condition.

Figure 3 is a fragmentary detail section on the line 3—3 of Figure 1.

Referring more in detail to the drawing, 5 indicates generally a litter or field stretcher of the type generally employed by military hospital units in the handling of casualties. As is conventional, the litter embodies sides poles 6, 6, respectively equipped with terminal handles 7, 7, and supporting therebetween the body-rest 8 of canvas or other suitable fabric. The fabric sheet 8 is of conventional or ordinary design, and is secured at its longitudinal edges to the poles 6, 6, in the well-known manner and as illustrated.

For use in combination with such litter or stretcher, and to form a constituent part thereof, I provide a fabric sheet 9. The function and purpose of this sheet 9 is to adequately protect from vesicant spray, as well as from rain and the

other elements, both the litter in its entirety and the occupant thereof.

To the effective accomplishment of the ends above stated, the sheet 9 is of a length sufficiently in excess of the over-all length of the litter so that when extended or draped over the litter, whether the latter be empty or occupied, the end edges of the sheet project beyond the extremities of the handles 7 at both ends of the litter. Consequently, when the litter is being transported, the hands of the attendants will grasp the handles 7 exteriorly of the protective cover sheet 9. This will cause the end edges of the folds 10, 11 of the sheet 9 to crease transversely of the sheet 9 in the manner clearly shown in Figure 1.

Obviously, such a creasing of the end edges of the protective cover sheet will serve to effectively seal these ends of the folded sheet and preclude entrance of vesicant spray and rain droplets between the folds. In such a manner does this protective sheet form an all-enveloping envelope for the litter when the latter is extended for use, and whether occupied or unoccupied by a casualty.

It is readily seen then that a litter so equipped in a manner above described and contemplated by my invention, will present an ever present and available effective medium that can readily be brought into use for protecting a casualty from the deleterious effects of vesicant spray and/or the elements while the casualty is being removed from the combat zone and/or the area contaminated by the chemical warfare agent.

It will be apparent that the cover sheet 9 may be of any suitable impervious fabric, such as oiled fabric, rubberized fabric, or other mustard-proof and waterproof material, the object, intent, and purpose of the sheet being to protect the casualty from vesicant spray and rain. Where available and found desirable, fabric impervious to vesicant vapors and rain but pervious to air may be used, however, preferably impervious fabric is used.

Preferably the cover sheet 9 is readily, bodily, separable from the litter or field stretcher. To that end one of the litter poles and the cover sheet along one of its longest edges are equipped with complementary fastener elements whereby a quick detachable connection therebetween can be effected. Any suitable type fastener 13 may be employed for the indicated purpose.

While it is not intended to so restrict the invention thereto, the advantages of having the cover sheet readily detachable are many. Litters can be used without the addition of the cover sheet, which latter can be readily attached to the litter for use wherever desired. Consequently, the added weight of the cover sheet may be dispensed with at will. Further, contaminated cover sheets may readily be replaced by clean sheets. These and other beneficial results will be appreciated by those skilled in the art.

Figure 1 is illustrative of an advantageous use of a litter or field stretcher equipped as above described in protecting a combat casualty in the event of chemical warfare action. As shown, the cover sheet 9 is spread over the entire area of the litter, completely covering, from head to foot, the occupant. The free ends or transverse edges of the sheet overlie the litter handles 7 and extend slightly beyond the free extremities of such handles. As a result, when the handles 7 are gripped by the attendants these free ends or transverse edges of the sheet 9 tend to fold

or crease downwardly, thus closing or substantially sealing the spaces between the cover 9 and body-rest 8 at the respective opposite ends of the litter or stretcher. The free longitudinal edge portion of the cover sheet 9 may be permitted to hang loosely from the adjacent side of the litter, or be extended across the underside of the litter with its free corners secured by the hands of the attendants gripping the pole handles 7. The disposition of the excess portion of the cover sheet 9 will, of course, be determined by the width of the sheet as compared with the width of the extended litter.

When stored or while being transported or carried to the place of use the litter is in the collapsed or rolled condition suggested in Figure 2. Under such circumstances, my cover sheet 9 serves effectively as a protective covering therefor, saving the folded litter from possible contamination by completely enveloping the folded structure. In this connection, it is to be noted that when the litter structure is folded, the cover sheet 9 is wrapped thereabout. The sheet 9 being of a length in excess of the over-all length of the litter, the handles 7 terminate short of the ends of the encompassing roll and consequently are not exposed for possible contamination. However, as an added precaution, the rolled sheet 9 may have the windings thereof at these projecting ends of the roll turned inwardly in an obvious manner for substantially closing the roll at said ends.

For the purposes above detailed, a cover sheet 9 materially exceeding in length the length of the litter, and ranging in width from 1½ to 2 times the extended width of the litter, will be found satisfactory.

Advantageously, the cover sheet of the invention may be used to protect the litter, blankets, and other forms of litter dressings, when the litter is extended or unfolded and has such blankets or dressings positioned thereon, as for example when the litter is being conditioned for immediate use. In such an event, the cover 9 is folded flat on the litter to rest either beneath the blanket or dressings or be superimposed on the blanket or other form of dressing, as may be found desirable.

Although I have herein illustrated and described the invention, as applied to field litters or stretchers, it will be readily appreciated that its field of application is not thereto restricted. For example, the cover sheet 9 of the invention when properly proportioned in size, may be used with equal advantage in association with a bed, cot, or similar form of body-rest by securing one marginal edge of the sheet to the selected rail. By so making the sheet available it, in the event of a gas attack, may be readily spread over the bed to cover the same together with the occupant thereof. Thus the invention may be practiced with all desideratum at base hospitals, and temporary treatment centers.

From the foregoing description, taken in connection with the accompanying drawing, it is thought the novel details, the manner of use of the invention, and the advantages thereof will be apparent to those familiar with this art.

It will also be understood that I have illustrated and described the preferred form of my invention, and that changes may be made in the form, construction and arrangement of the parts. Consequently, my invention is not limited to this embodiment and is best defined by the following claims.

What I claim as new, and desire to secure by Letters Patent is:

1. A litter, a cover sheet, and complemental fastener elements at one edge of the cover sheet and at one side of the litter detachably securing said cover sheet to said one side of the litter, said cover sheet being of a material impervious to vesicant vapors and resistant to rain, and of a length and width exceeding the length and width of the litter so that when wrapped about the occupied or unoccupied litter excess marginal portions of the sheet extend beyond the extremities of the litter to provide for complete envelopment of the litter and occupant as a protection against contamination of the litter

and the effects of vesicant vapors on the occupant.

2. In combination, a litter, and an enveloping protective sheet of impervious material, said sheet being detachably secured at one longitudinal edge thereof to the litter and adapted to be wrapped about the extended unoccupied or occupied litter when the litter is in use, and to be wrapped about the litter when the latter is in folded condition; and said sheet being of a length exceeding the length of the litter to protect the handles thereof when the sheet is in the referred to spread and wrapped conditions, respectively.
